UNITED STATES PATENT OFFICE.

ARCHIBALD L. BROWN, OF CHICAGO, ILLINOIS.

SIGN.

SPECIFICATION forming part of Letters Patent No. 665,309, dated January 1, 1901.

Application filed August 17, 1900. Serial No. 27,126. (No model.)

To all whom it may concern:

Be it known that I, ARCHIBALD L. BROWN, a citizen of the United States, residing in Chicago, in the county of Cook and State of Illinois, have invented a new and useful Improvement in Signs, of which the following is a specification.

This invention relates to improvements in that class of signs which are readable by day-
10 light and are rendered visible at night by illumination, and especially to electrically-illuminated signs.

The invention consists in the novel features of construction hereinafter fully set forth, and
15 illustrated in the accompanying drawings, in which—

Figure 1 is an elevation of my improved sign. Fig. 2 is a vertical longitudinal section, and Fig. 3 a transverse vertical section of the
20 same. Fig. 4 is a section similar to Fig. 3, showing a modified construction. Fig. 5 is a partial vertical transverse section enlarged.

In said drawings, A represents a suitable casing for the sign, which may be suspended
25 by chains B and a central longitudinal tube B' or otherwise supported. In the front of this casing is a glass plate C, rendered opaque by a layer of heavy paint C', except where the letters or other designs occur, so that it
30 cuts off the rays of light from the lamps used in illuminating the sign, with the exception of such as escape through the letters or design. The glass is secured to any suitable surrounding frame, such as that shown at D,
35 having a retaining-channel D', in which the plate will be securely held.

The outlines of the letters or design are indicated by rows of jewels E, secured to the outside of the plate. I prefer to attach the
40 jewels to the outside of the plate, as clearly shown at Fig. 5, as I find by experiment that not only are the jewels much more brilliant when thus attached than when they are attached to the inside of the plate—as, for instance, in the manner shown in the patent to Evans, No. 653,003—but the sign can be read more easily and clearly from a sidewise point of view. As will be understood, the plate C is transparent where the jewels are applied,
45 so that the rays from the lamp may pass through the jewels.

It has been customary heretofore to illuminate these signs by means of lamps placed directly back of the letters, and as a consequence the letters are unevenly lighted, some 55 portions of the sign being less brilliant than others. I have removed this objection by placing the lamps F in the top of the casing and beneath a reflector G, whereby the entire space inside the casing is not only rendered 60 very light, but the light is evenly distributed, no one part of the sign receiving more than another part, so that the effect of the sign to the beholder is greatly improved. The series of lamps and the reflector are arranged longitudinally of the casing, as seen at Fig. 2, and are located wholly above the highest part of the letters. It is desirable where the sign is a double one—that is, with two letter-
65 plates C, as at Figs. 3 and 4—that a separate 70 series of lamps and reflectors be provided for each plate.

A further feature of my improvement will be found in the provision of means for causing flashes of light to pass up and down the 75 series of jewels. These means consist of a moving mirror or mirrors located in the casing and directly back of the jeweled letters. In the simplest construction a mirror H is secured in a swinging frame H', hinged in the 80 upper part of the sign-casing and receiving a slow to-and-fro movement from an electric or other suitable motor J. This causes flashes of light to traverse the signs in vertical directions, both in the day-time and at night, 85 and attracts the attention of passers-by to them oftentimes when they would otherwise be unnoticed. In double signs the mirrors H may be placed back to back in the same frame H' as illustrated at Fig. 5, and these mirrors 90 may be made of colored glass, if desired, so that the flashes passing over the sign will be similarly colored. A modification of this feature of the sign is shown at Fig. 4 and consists in securing a series of mirrors H to a 95 revolving shaft H², so that they stand radially of the shaft and will cause successive flashes of light to pass over the sign as they pass the latter. These radiating mirrors may be variously colored, so that successive flashes 100 caused by them will be unlike in color. It is desirable to duplicate the mirrors H in this

construction as well as in the other, and thereby enable them to cast flashes upon both faces of the sign.

The casing is desirably provided with a door K in its bottom, allowing access to the interior of the casing. The motor and the lamps may all be supplied with electrical energy by the wires L L.

L' represents an arched plate forming part of the top of the casing.

I claim—

1. The illuminated sign having the letters or design formed by jewels secured to a glass plate which is opaque except where the jewels occur, and also having a moving mirror for flashing light over the jewels both by day and by night, substantially as specified.

2. The illuminated sign having the letters or design formed by jewels secured to a glass

plate which is opaque except where the jewels occur, means for illuminating the sign at night, and a moving mirror positioned to catch both the rays of said illuminating means and the daylight-rays, and to flash both over the jewels, substantially as specified.

3. The illuminated sign having the letters or design formed by jewels secured to a glass plate which is opaque except where the jewels occur, means located above the jewels for illuminating them at night, and a moving mirror positioned to catch both the daylight-rays and the rays of said illuminating means, and to flash them over the jewels, substantially as specified.

ARCHIBALD L. BROWN.
